UNITED STATES PATENT OFFICE.

FREDERICK A. YEAGER, OF THORNBURG, PENNSYLVANIA, ASSIGNOR OF ONE-FOURTH
TO DONALD V. McCONNEL, OF NEW BRIGHTON, PENNSYLVANIA.

WEATHER-STRIP.

979,631.

Specification of Letters Patent. Patented Dec. 27, 1910.

Application filed June 29, 1909. Serial No. 505,099.

To all whom it may concern:

Be it known that I, FREDERICK A. YEAGER, a resident of Thornburg, in the county of Allegheny and State of Pennsylvania, have 5 invented certain new and useful Improvements in Weather-Strips, of which the following is a specification.

My invention relates to improvements in weather-strips for windows, doors, and other 10 structures.

An object of the present invention is to provide a simple and efficient weather-strip particularly designed to be employed at the sides of and at the bottom of a window- 15 sash, although it may be employed for other purposes.

In the accompanying drawing, which illustrates an application of my invention, Figure 1, is a broken perspective view of a 20 portion of a window-frame and a sash showing my improved weather-strip in connection therewith; and Fig. 2 is a detail sectional view of the weather strip.

Referring to the drawing, 1 designates a 25 window-sash, and 2, the frame-work of a well known construction.

As illustrated and as preferred the weather-strip comprises a flat entering-member 3, a U-bent portion 4, and a portion 30 or member 5, the latter being inclined with relation to the entering-member 3, all made as an integral structure from some suitable metal.

Extending from the bent portion and projecting outwardly in a plane parallel to the plane of the inclined-member 5, I employ a piece or strip 7 of some suitable yielding material, as cloth, felt, or rubber.

As particularly shown by Fig. 2, I provide 40 an extension 8 to the inclined-member 5, and clasp the end of the strip 7 between said extension 8 and member 5.

In some instances it is desirable to form

a slight cut or channel in the lower sill and the side sills of the window-frame, as shown 45 at *x* and *y* to receive the entering edges of the members 3. After the strips are in position they may be secured by small nails as shown at *n*.

By having the member 5 inclined with 50 respect to the member 3 and the strip 7 disposed as shown, I provide a construction having a spring action to take up the play of the sash, and at the same time this construction will prevent the strip from buckling 55 when the sash is moved.

What I claim is:

1. A weather-strip having a curved-portion, a flat entering-member extending from the curved-portion in one direction, a second 60 member extending from the curved-portion in an opposite direction and inclined with relation to the entering-member to form a spring, said second member bent upon itself, and a strip of yielding material projecting 65 from the curved portion and having a portion held by the bend of the second member.

2. A weather-strip having a curved-portion, a flat entering-member extending from the curved-portion in one direction, a second 70 member extending from the curved-portion in an opposite direction and inclined with relation to the entering-member to form a spring, said second member provided with an extension, and a strip of yielding material held between the inclined-member and its extension, projecting from the curved-portion and bent against the extension to 75 form a double thickness of felt.

In testimony whereof I affix my signature 80 in presence of two witnesses.

FREDERICK A. YEAGER.
